UNITED STATES PATENT OFFICE.

EDWARD SANDERS, OF MONROE, MICHIGAN.

PUMP.

1,370,048.

Specification of Letters Patent.

Patented Mar. 1, 1921.

Application filed May 6, 1920. Serial No. 379,205.

To all whom it may concern:

Be it known that I, EDWARD SANDERS, a citizen of the United States, residing at Monroe, in the county of Monroe and State 5 of Michigan, have invented certain new and useful Improvements in Pumps, of which the following is a specification.

This invention relates to air pumps, and more particularly to that class or variety of 10 pumps operated by hand for the purpose of inflating small pneumatic tires, such as bicycle and automobile tires, and has for its object to provide a method of attaching the tubes or barrels to the base and to the yoke 15 or top, which will produce an air tight and rigid connection, avoiding threading, and providing a much cheaper and stronger attachment than heretofore known, and one which cannot leak under any circumstances. 20 The invention also contemplates the use of an automatic oiling device for the pump, of original construction and cheap design, which is very effective in keeping the plungers well oiled for almost an indefinite period, and at the same time to utilize a minimum supply of lubricating fluid.

With these and other objects in view, which will be more particularly referred to hereinafter, I now refer to the attached 30 drawings, in which,

Figure 1 represents a vertical section of my improved pump, showing the oiling device attached thereto.

Fig. 2 is a longitudinal section on the line 35 2—2, of Fig. 1.

Fig. 3 is a longitudinal section along the line 3—3 of Fig. 1.

Fig. 4 is a vertical section showing the base or pedestal, and

Fig. 5 a perspective view of one of the 40 rings used in fitting the barrels into the base and top.

The invention contemplates the use of the ordinary class of hand pump with the improvements in the construction thereof as 45 indicated herein. 1 denotes the base of the pump having integral therewith, the cups or receptacles 2 and 3 into which are fitted the barrels or the cups 4 and 5, in the manner 50 to be described hereinafter. The upper ends of the barrels or tubes 4 and 5 are fitted into the top or yoke 6, as will be more fully explained hereinafter. The barrel or tube 4 has within it the piston 7, which is 55 cured at its top to the handle 8, having affixed to its bottom the washer or plunger

member 9, which is preferably composed of leather. This member 9 is narrow at the top and wide at the bottom, so that when the piston or plunger 7, is on the down stroke it will force the air down through the barrel or tube 4, through the duct or canal 10, and up into the barrel or tube 5. The arrangement of the parts in the construction and operation of the barrel or tube 5 is 60 somewhat similar to the barrel and piston heretofore described. It has within it the piston 11, which is secured at its upper end to the handle 8, and having fixed to its lower end the washer or plunger mechanism 65 12, which is also preferably composed of leather. This washer mechanism 12 is different from that shown at 9 in the tube 4, in that it is narrow at the bottom and wide at the top, also having therein the one-way 70 valves 13. These valves 13 are closed automatically on the up stroke of the piston and are open on the down stroke. Thus it will be seen that when the pistons 7 and 11 are forced down, the plunger 9 propels the air 75 through the duct or canal 10, as heretofore set forth, into the barrel or tube 5, and the valves 13, being open, the air is further forced up through the said valves through the barrel 5, and the aperture 14, 80 and out through the pipe or tube 15. On the up stroke of the pistons 7 and 11, the valves 13 being closed, the air in the tube 5, is forced up through the aperture 14, and into tube 15. Therefore, it will be seen 85 that on both the up and down strokes of the pistons, there is a continuous flow of air from the pump which only stops when the manipulation of the pump is ended.

Approaching now the more pertinent part 90 of my invention, it will be seen that the lower annular walls 16 and 17, or the cups or receptacles 2 and 3, are downwardly diverging. Into the cups 2 and 3, are placed the rings 18 and 19, a perspective view of 100 one of which is shown in Fig. 5. It will be noticed that these rings also diverge downwardly, and when placed within the cups, the sides thereof run parallel to the downwardly diverging annular walls of the 105 cups. These rings are smaller in diameter than the inside walls of the cups. In fixing the barrels into the cups, the rings are first placed therein, after which the barrels are forced in, the cylindrical wall of the barrels being placed between the downwardly 110 diverging annular walls of the cups and the

downwardly diverging rings. Thus as pressure is brought to bear for inserting the barrels firmly into position, the bottoms of the barrels will necessarily expand or flare, 5 and when driven down to the bottom of the cups will form a perfectly air tight fit, without use of the ordinary threaded arrangement found in pumps of a similar character.

10 The top of the barrel 4, is fitted into the yoke or top 6, in a similar manner, 20 representing the upwardly diverging cup in the yoke or top and 21, the ring similar to those heretofore described.

15 Bolted to the other end of the top or yoke 6 is the part 22, having therein the air vent or aperture 14. The barrel or tube 5 is fitted into this member 22 in a manner similar to the fitting of the other barrel. The 20 part 22 has therein a cup or receptacle with the upwardly diverging walls 22^a, into which is placed the ring 22^b, these walls and the ring being similar in shape, construction, use and operation as those previously described.

25 The construction and operation of the automatic oiler is as follows: 22 is a small cylinder secured in a conventional manner into the base and the top or yoke 6, and the bottom of which rests upon the shoulders 23, of the base and directly over the duct 24. In the bottom of the cylinder 22, there is placed a small quantity of lamp wicking, or other absorbent substance indicated at 25, the rest of the cylinder being filled with oil. 30 This oil gradually soaks through the absorbent substance 25, and very slowly, drop by drop, drips down into and through the duct at 24, into the duct 10, and, as the air is forced backward and forward, it carries 35 with it a small amount of oil, which finally adheres to the inner wall of the barrels 4 and 5, thus lubricating the plunger mechanism and insuring a long lasting quantity of oil.

40 Thus it will be perceived that I have invented a pump of air tight construction avoiding the use of screw threads on the barrels and base, rendering leakage impossible, providing a connection that is stronger and better in every way than those heretofore invented, but which is much less expensive, and with an automatic self oiler which insures the easy operation and indefinite existence of the mechanism without the necessity of repeatedly taking the device apart to 45 lubricate the parts.

50 Having thus fully described my invention, what I claim is:

55 1. In a pump, the combination of two

barrels, a base having integral therewith 60 cups or receptacles the lower annular walls of which are downwardly diverging and into which are fitted the lower ends of the barrels, downwardly diverging rings within 65 said cups or receptacles for causing the lower ends of the said barrels to flare when forced in to the cups or receptacles and to thereby hold them in fixed and rigid position, a yoke or top having at one end thereof 70 a cup or receptacle with upwardly diverging walls into which is fitted the upper end of one of the said barrels, a ring having upwardly diverging walls, which causes the upper end of said barrel to expand or flare as it is forced into position, a member secured to the other end of the said top or yoke having therein an air vent, the said member having also a cup or receptacle the upper annular walls of which are upwardly 75 diverging and into which is fitted the upper end of the other said barrel, and a ring with upwardly diverging walls which causes the upper end of the other said barrel to expand or flare when the same is forced into position.

2. An air pump comprising a top or yoke, 80 a base, two barrels secured in permanent position to the said top and base, and an automatic self oiling device secured at its top to the said yoke and at its bottom to the said base.

90 3. An air pump comprising a base, a yoke, barrels or tubes held in position to the base and to the yoke, and a hollow cylinder adapted to hold lubricating fluid, fixed to the said device whereby lubricating medium 95 is permitted to travel into the said barrels or tubes and thereby lubricate the working parts of the said device.

4. In a pump the combination of a yoke, 100 a base, barrels or tubes secured in fixed position to the said yoke and base, cups integral with the said base into which the bottoms of the said barrels are fitted, a duct leading from one cup to the other, a lubricating device fixed into the base, and a second duct 105 in said base, the second said duct communicating at its bottom to the first said duct and having an annular shoulder on which the said oiling device rests, so that oil or other lubricating medium is allowed to pass 110 from the said oiling device through the said second duct into the first said duct and thence into the said barrels.

In testimony whereof, I hereunto affix my signature.

EDWARD SANDERS.
